UNITED STATES PATENT OFFICE.

JOSEPH LEDWINKA, OF PHILADELPHIA, PENNSYLVANIA.

ТИЛТИНГ ВАГОН-БОДИ.

1,139,456.

Specification of Letters Patent. Patented May 11, 1915.

Application filed November 22, 1912. Serial No. 732,833.

To all whom it may concern:

Be it known that I, JOSEPH LEDWINKA, a citizen of the United States, residing at Philadelphia, county of Philadelphia, State 5 of Pennsylvania, have made a certain new and useful Invention in Tilting Wagon-Bodies, of which the following is a specification.

This invention relates to wagon bodies, 10 and particularly to wagon bodies of the tilting type.

The object of the invention is to provide a tilting wagon body which is strong and durable, simple in construction and economical to manufacture.

A further object is to provide a wagon body of the nature referred to and which is composed of sheet metal plates formed and suitably pressed into the desired shape and 20 assembled together and strengthened by ribs, with all parts welded together at their joints.

Other objects of the invention will appear more fully hereinafter.

The invention consists substantially in the construction, combination, location and relation of parts, all as will be more fully hereinafter set forth, as shown in the accompanying drawings, and finally pointed 30 out in the appended claims.

In the accompanying drawings:—Figure 1 is a view in side elevation of a tilting wagon body embodying the principles of my invention. Fig. 2 is a view in elevation 35 of the rear end of the same. Fig. 3 is a similar view of a portion of the front end. Fig. 4 is a broken view in vertical section on the line 4, 4, Fig. 2. Figs. 5, 6, 7 and 8 are broken detail views in section on the 40 lines 5, 5; 6, 6; 7, 7; and 8, 8, respectively.

In some forms of delivery wagons the wagon body is supported so as to be tilted in order to spill out the coal, sand, grain or other material being transported thereby. 45 Such wagon bodies are subjected to severe usage which quickly injures them unless they are made so heavy as to be expensive to manufacture and more difficult to handle or to haul.

50 It is among the special purposes of my present invention to provide a wagon body of the tilting type which secures lightness without sacrificing anything of strength and rigidity, which is economical to manu-

facture and which is able to withstand without injury the hard rough usage to which such bodies are ordinarily subjected.

In carrying out my invention I construct the body out of sheet metal plates, suitably cut and shaped and assembled together and 60 welded at the joints thereof, and I stiffen and strengthen the body by applying channel ribs to the exterior surface and along the open edges of the body. I also provide the body with a hinged door in the rear end 65 thereof and with locking means at its front end to prevent the body from tilting until the lock is released and I provide a lock for the hinged end door to prevent said door from opening until said lock is released. 70

Referring to the accompanying drawings, numeral 10, designates the sheet metal plates forming the sides and bottom of the wagon body, 11, the sheet metal front end plate, and 12, the sheet metal plate connecting the 75 side plates at the rear end of the body above the doorway therein. The plates or sheets forming the sides of the body are flared in opposite directions or away from each other at their upper edges, so as to give the body 80 opening a flared mouth. The metal sheets forming the sides and bottom of the body are preferably of such length as to extend all the way from one outwardly flared edge 13, to the other, being suitably bent intermediate its ends to form the transverse body shape. These sheets or plates are assembled and welded together at their meeting edges to form, in effect, a substantially integral 85 sheet metal body throughout, the edges of 90 the front end plate 11 and of the rear end plate 12 being similarly secured to the edges of the side plates 10, respectively proximate thereto. In practice, however, and in order to secure strength and rigidity, at the edges 95 of the side and end plates, where they come together, I prefer to apply metal channel shaped ribs thereto. Such a corner or angle rib is shown at 14 between the side and end plates 10, 11, see Fig. 7. In this case the 100 edge of one of the plates 10, 11, is bent so as to receive the flatwise bearing contact of the other plate, adjacent its edge, as shown, and the edge-lip 15, of the channel rib is then placed flatwise against the body plate, 105 while at its other edge the channel rib is provided with a flange 16, which lies flatwise against the surface of the other body

plate adjacent its edge, all the joints of these parts being welded. At the rear end of the wagon body a similar channel rib 17, is employed to join the meeting edges of the body plates 10, 12. In this case the plates 10, 12 are brought edge to edge and in the desired angular relation while the channel rib 17 is applied over the corner or angle so formed by the plates, with its edge flanges 18, 19 respectively bearing flatwise against the surfaces of the body plates 10, 12, adjacent their edges, as clearly shown in Fig. 5.

At suitable points intermediate the ends 15 of the body I also provide channel ribs 20, and arrange the same to extend vertically of the sides and on the outside surface thereof, and transversely across and underneath the bottom of the body, as seen in 20 Figs. 2 and 3, said ribs being made in pairs, the mates of each pair being welded together at their meeting ends underneath and at approximately the midwidth of the wagon body. These ribs 20 are preferably 25 of substantially U-shape in cross section, as indicated in Fig. 6, and the edge flanges 21, 22, thereof lie flatwise against the outer surfaces of the body plates and are welded thereto. The ribs 20, are also preferably 30 tapered toward their upper ends and the extreme upper ends thereof are bent outwardly, as shown, to conform to the outward flare 13 of the wagon body.

The plate 12, which connects the sides of 35 the wagon body at its rear end, is connected at its end-edges to the side edges of the body sides only at the upper portions thereof, said plate extending downwardly only a short distance, thereby leaving a space between its lower edge and the floor of the body sufficient to form a doorway in the rear end of the wagon. The upper edge of 40 this end plate 12 is strengthened and stiffened by a channel rib 23, the upper edge of plate 12 being received between the lips 24, 45 25, of said channel rib, as seen in Fig. 4. The lower edge of plate 12, is, similarly strengthened and stiffened by a channel rib 26, which receives the lower edge of plate 50 12 between its lips 27, 28, the joints of the edges of the plate 12 and its respective ribs being welded. This makes a very strong, rigid, but light structure.

To the exterior surface of the end plate 55 12 is riveted or otherwise secured the metal brackets 29, which extend vertically across the end plate 12 and not only afford strengthening means therefor but also they afford means for hinging thereto a rear end door for the vehicle. This rear end door comprises a plate 30 of sheet metal having its lower edge bent into a channel rib formation, as indicated at 31, Figs. 4 and 8 for the purpose of securing strength and rigidity, the flange 32 of the box rib channel

31 lying flatwise against the inner surface of the plate 30. Metal ribs 33 are riveted or otherwise suitably secured to the exterior surface of the door plate 30 to strengthen the same and to afford hinge connections to 70 the brackets 29. In the form shown the brackets 29 carry a hinge rod 34 which is pivotally engaged by the upper ends of brackets 33. The rear end door may be locked or retained in closed position in any 75 suitable or convenient manner. I have shown a simple arrangement wherein a locking lever 35, mounted upon the side of the vehicle body has its hooked end arranged to engage over a lug 60 carried at the edge 80 of the end door. If desired a locking lever 35 may be located on each side of the door. By suitably releasing the engagement of the locking levers from the lugs 60, the door will be free to open.

I have shown my invention as applied to a vehicle body of the tilting type, the front end of the body being raised in any suitable or convenient manner in order to tilt the same to permit the contents of the body to 90 be delivered therefrom through the doorway at the rear end. To this end the body or the side members 36 thereof, which are suitably secured thereto through brackets 37, carry hinge brackets 38, which take bearing upon a pivot shaft or rod 39, suitably supported in standards 40, carried by a frame, a portion of which is indicated at 41, and forms part of its chassis. By elevating the front end of the body said body tilts 100 about the pivot rod or shaft 39 as an axis. A lug or bracket 42 carried by the chassis 41 may serve as a seat to support the body of the vehicle when in untilted position. If desired, and in order to lock the body 105 against tilting movement, a locking lever 43 may be arranged to engage a lug or projection 44 upon the side of the body at its front end.

If desired and in order to suitably brace 110 the sides of the body intermediate the ends thereof, and particularly at a point near the upper edges of said sides, a brace rod 45 may be employed and passed through suitable lugs 46, 47, see Fig. 2, and clamped 115 in place by a nut 48, or in any other suitable or convenient manner. This affords a most simple and efficient arrangement for bracing the side walls of the vehicle body.

The bottom plate 50 of the wagon body 120 is formed into a channel formation as indicated at 51, Fig. 4, at the rear end of the body. This affords an efficient strengthening and rigidity at this point. The upper edge of the door plate 30 has a channel rib 125 52 applied thereto for strengthening purposes.

Having now set forth the object and nature of my invention and a construction embodying the principles thereof, what I 130

claim as new and useful and of my own invention, and desire to secure by Letters Patent of the United States is:—

- 5 1. A tilting wagon body composed of sheet metal plates each shaped to form a portion of the side walls and bottom of the body, the said plates being assembled edge to edge, and having channel shaped reinforcing members applied to the exterior surface thereof at the joints, said channel members having laterally extending edge flanges respectively applied flatwise against the surfaces of adjacent body plates, all of said parts being integrally secured together.
- 10 10 2. A tilting wagon body composed of sheet metal plates each shaped to form a

transverse portion of the body, said body having a doorway opening therein, the body plate adjacent the doorway opening being bent into channel shape to form the sill of 20 the doorway opening, the free edge of the channel being formed into a flange to lie flatwise against the bottom surface of the body plate, and integrally secured together.

In testimony whereof I have hereunto 25 set my hand in the presence of the subscribing witnesses, on this 29th day of October A. D., 1912.

JOSEPH LEDWINKA.
